WALTER VAN B. ROBERTS

BY *W. B. Roberts*
ATTORNEY

UNITED STATES PATENT OFFICE

WALTER VAN B. ROBERTS, OF PRINCETON, NEW JERSEY, ASSIGNOR TO RADIO CORPORATION OF AMERICA, A CORPORATION OF DELAWARE

SUPERHETERODYNE RECEIVER CONTROL

Application filed November 20, 1929. Serial No. 408,425.

My present invention relates to heterodyne receiving systems, and more particularly to an improved type of superheterodyne receiver.

5 In a copending application, Serial Number 351,404, filed on March 30, 1929, there was described and claimed a superheterodyne receiver in which there was employed for tuning purposes only a single, variable circuit 10 element whereby the necessity of utilizing a uni-control gang of tuning elements was eliminated. There was further disclosed and claimed in this copending application a superheterodyne receiver free from "image" frequency interference, (that is to say, free from interference engendered by interfering stations whose frequencies are as much on one side of the heterodyne frequency as the desired signal frequency is on the other side).

15 20 These image frequencies were eliminated by subjecting the collected signal energy to a fixed filter circuit, the filtered energy then being heterodyned with local oscillations of a frequency above the broadcasting range, 25 there being further employed an intermediate frequency sufficiently high so that all the image frequencies of the desired stations were located entirely above the frequency range of the desired stations, which permitted a low 30 pass filter to separate the desired stations from their images.

In the case of broadcast stations having frequencies from 550 to 1500 kilocycles, it is obvious that the lowest intermediate frequency which separates the desired signals from their images is 475 kilocycles.

35 The intermediate frequencies employed in a system described in my aforementioned copending application may be conveniently divided into three ranges. First, the range which includes frequencies from 475 to 550 kilocycles; this range is satisfactory except in three respects:

40 45 (1) The oscillator frequencies required include part of the broadcast range, and therefore care must be taken to prevent interference between such oscillator and other receiving sets in the neighborhood.

50 (2) The range of images is not separated by much of an interval from the range of

signals, thus making it more difficult to separate the highest signal frequency from the lowest image frequency effectively.

(3) The intermediate frequency may be produced as beats between certain pairs of 55 undesired stations.

Secondly, it may be considered possible to locate the required intermediate frequency within the range of broadcast signal frequencies. This would be a good arrangement, if there were any frequencies in the broadcast range free from transmitting stations. Obviously, this is not practicable in present day broadcasting practice, unless a channel within the broadcasting range can 60 be officially set aside for emergency situations, it being observed that an intermediate frequency could be employed within this channel since the occurrence of emergency calls would be very few compared to the 65 useful reception on this channel.

Finally, the third possible location of the intermediate frequency is above the broadcast range. This location has the advantage that the local oscillator never operates at any broadcast frequency and hence there is less chance of its possessing interfering radiation characteristics. Again, the separation of signals from image frequency is easily accomplished in this range. It should be observed that with screen grid tubes a high 70 intermediate frequency can be readily amplified, and by employing low loss circuits in sufficient number a good degree of selectivity 75 can be obtained.

80 Now, I have found that there still remains one drawback to the utilization of a high intermediate frequency, and it is to the elimination of this disadvantage that the present invention is directed. I have found that 85 when an intermediate frequency above the broadcast band is employed and no selection between broadcast signals is used, there are likely to exist one or more combinations of transmitting frequencies, the sum of whose 90 frequencies is equal to the intermediate frequency being employed.

95 Again, it is quite likely that there will be a certain small number of transmitting stations having harmonics approximately equal 100

to the intermediate frequency. It is quite obvious that in such cases, intermediate frequency currents will be produced without the cooperation of the heterodyne oscillations, and if the effect is sufficiently pronounced 5 audio signals of certain stations will be heard independently of the local oscillator adjustment. Even if these interfering signals are not heard as audio signals, whistles will be 10 produced as the oscillator tuning dial is tuned past certain positions.

As stated above, the present application is directed towards eliminating the sources of interference specified in the foregoing paragraph. I have discovered a method of, and 15 devised means for, obtaining beat frequencies in a heterodyne system from the interaction of a local oscillator with desired incoming signals, without at the same time producing beat 20 currents between two or more incoming signal frequencies, thus eliminating interference caused by applying all frequencies (undesired as well as desired stations) simultaneously upon the frequency changer.

Accordingly, it is one of the main objects 25 of the present invention to provide a highly selective, receiving circuit in which there is employed, for tuning purposes, only a single, variable circuit element, which circuit operates on the superheterodyne reception principle and is free from "image" frequency interference, and is further provided with means for obtaining beat frequencies from 30 the heterodyning of a local source of oscillations with incoming signal frequencies without simultaneously producing beat currents between incoming frequency energy and high frequency energy other than energy from 35 said source of local oscillations.

Another important object of the invention 40 is to provide a method for obtaining beat frequencies from the interaction of a local oscillator with an incoming signal frequency without at the same time producing beat currents between two incoming signal frequencies, which consists in collecting one or more signal frequencies, impressing all the signal frequencies upon a pair of frequency changer tubes, balancing out beat currents caused by 45 interacting signal frequencies, and cumulating the beat currents caused by the interaction of the signal frequencies and the local heterodyne frequency.

The novel features which I believe to be 50 characteristic of my invention are set forth in particularity in the appended claims, the invention itself, however, as to both its organization and method of operation will best be understood by reference to the following description taken in connection with the drawing in which I have indicated diagrammatically a circuit organization whereby my invention may be carried into effect.

Referring now to the drawing which shows 55 diagrammatically a superheterodyne receiver

circuit embodying my invention, there is shown a grounded antenna circuit 3, 4. The energy collected in the antenna circuit is impressed upon the input terminals of a low pass filter, the latter comprising a plurality of filter sections made up of inductances 1 and capacities 2, and not passing frequencies above the broadcast range. The filter is equipped with terminating resistances R_1 and R_2 at each end, each resistance being connected in shunt with its adjacent capacity. The resistance R_1 is connected in the antenna circuit, as shown. 70

The output of the filter is connected through a capacity C and a leak R_3 to the midpoint 5 of the inductance 6, the latter being connected in series with the two control electrodes 7, 7' of the space discharge tubes 8, 8'. A variable capacity C' , shunted across the inductance 6 determines the tuning of the oscillator circuit. The circuit which includes the tubes 8, 8', the tuned input circuit 6, 6', tickler coils 16, 16 and by-pass condensers 17, 17 is 75 considered the oscillator circuit.

The cathodes of the tubes are connected in 80 series through a resistance 9, which is tapped by a grounded slider member P. The resistance 9 is shunted by a series connection of two by-pass capacities 10, 10', the connection between the capacities being grounded. The midpoint connection to the inductance 6 causes the control electrodes 7 and 7' to be 85 energized in opposite phase.

The anode circuits of the two tubes are 90 connected differentially with respect to a tank circuit I, the latter including an anti-resonant connection of a capacity 11 and an inductance 12, the latter being tapped at its midpoint 13 by a lead 14 connected to a 95 source of anode current "B". The circuit I is fixedly tuned to the intermediate frequency being employed. The function of the tank circuit I is to balance out energies coming from the tubes in like phase, but to cumulate 100 the desired beats which are in opposite phase. 105

The anode of each tube is connected to a point 15, between the capacity 11 and inductance 12 through a coil 16, regeneratively coupled to the inductance 6. Each anode lead to the circuit I is grounded through a high 110 radio frequency by-pass capacity 17. The inductance 12 is coupled to an inductance 18, the latter being disposed in the input circuit of the intermediate frequency amplifier J, 115 the inductance 18 being shunted by a capacity 19 for tuning the circuit J to the intermediate frequency employed. It is to be understood that the circuit J may be connected to the usual amplifier, detector and utilization circuits, not shown herein for the sake of simplicity.

If the oscillator tubes 8, 8' are not functioning, all currents in the anode circuits due to incoming signals balance out in circuit I, so that no voltage of any frequency 120

can be produced in circuit J coupled thereto. When the oscillator tubes 8, 8' are functioning, however, such components of the anode currents as depend upon the phase of oscillator voltage will accumulate in tank circuit

5 I. Thus, beats will be produced between the incoming signals and the oscillator frequency (which is what is desired), while beats will not be produced between incoming signal frequencies themselves.

10 The condenser C and grid leak R₃ are provided as a well known means for maintaining bias on the grids, and a resistance K may be inserted between point 5 and capacity C, if necessary, to prevent parasitic oscillation. The tubes 8 and 8' must be maintained in proper balance, and slider P is one expedient of adjusting the relative outputs of the two tubes to obtain perfect balance.

15 20 While I have indicated and described one arrangement for carrying my invention into effect, it will be apparent to one skilled in the art that my invention is by no means limited to the particular organization shown and described, but that many modifications may be employed without departing from the scope of my invention as set forth in the appended claims.

What I claim is:

30 1. A method for obtaining beat frequencies from the interaction of local oscillations with an incoming signal frequency without at the same time producing beat currents between two incoming signal frequencies which consists in collecting a plurality of signal frequencies, impressing all the signal frequencies upon a pair of frequency changer tubes, balancing out currents in the outputs of the tubes in like phase, and cumulating desired beat currents in the outputs of the tubes which are in opposite phase.

35 40 45 2. A superheterodyne circuit comprising means for collecting signal energy, a filter circuit for suppressing undesired signal frequencies, a frequency changing circuit for producing beat currents in like phase and opposite phase, and a tank circuit for balancing out the currents in like phase and cumulating the beat currents in opposite phase.

50 55 60 3. A superheterodyne circuit comprising means for collecting signal energy, a filter circuit for suppressing undesired signal frequencies outside the broadcast range, a frequency changing circuit for producing beat currents in like phase and opposite phase, and a tank circuit, resonant to a frequency above the broadcast range, for balancing out the currents in like phase and cumulating the beat currents in opposite phase.

65 65 4. A superheterodyne circuit comprising means for collecting signal energy, a filter circuit for suppressing undesired signal frequencies, a frequency changing circuit for producing beat currents in like phase and opposite phase, and a tank circuit for balanc-

ing out the currents in like phase and cumulating the beat currents in opposite phase, the frequency changing circuit including a pair of tubes between the filter and the tank circuit.

70 5. A receiver comprising means for collecting radio frequency energy including broadcast frequencies, means for suppressing frequencies outside the broadcast range, a frequency changing circuit for producing beat currents in like and unlike phase, and an additional circuit for balancing out currents in like phase.

75 6. A receiver comprising an aperiodic means for collecting radio frequency energy so including broadcast frequencies, means for suppressing frequencies outside the broadcast range, a frequency changing circuit for producing beat currents in like and unlike phase, and an additional circuit for balancing out currents in like phase.

80 7. A receiver comprising an aperiodic means for collecting radio frequency energy including broadcast frequencies, means for suppressing frequencies outside the broadcast range, a frequency changing circuit including a pair of space discharge devices, for producing beat currents in like and unlike phase, and an additional circuit for balancing out currents in like phase.

85 8. A receiver comprising an aperiodic antenna for collecting radio frequency energy including broadcast frequencies, filter means for suppressing frequencies outside the broadcast range, a frequency changing circuit for producing beat currents in like and unlike phase, and an additional circuit for balancing out currents in like phase.

90 95 100 9. A receiver comprising means for collecting radio frequency energy including broadcast frequencies, means for suppressing frequencies outside the broadcast range, a frequency changing circuit for producing beat currents in like and unlike phase, and a tank circuit resonant to a frequency outside the broadcast range for balancing out currents in like phase.

105 110 115 10. A receiver comprising means for collecting radio frequency energy including broadcast frequencies, means for suppressing frequencies outside the broadcast range, a frequency changing circuit for producing beat currents in like and unlike phase, and a tank circuit resonant to a frequency outside the broadcast range for balancing out currents in like phase and cumulating currents of unlike phase.

120 125 130 11. A superheterodyne receiver comprising an aperiodic antenna for collecting radio frequency energy including broadcast frequencies, a frequency changing circuit, including a pair of electron discharge tubes having a common input and output circuit, for producing beat currents in like and unlike phase, and a resonant circuit in the common out-

put circuit of said tubes, resonant to a frequency above the broadcast range, for balancing out currents in like phase, and cumulating currents of unlike phase, and a circuit, resonant to a desired beat frequency, coupled to said last mentioned resonant circuit.
